Primary Examiner—Joel Sincavage[57] **CLAIM**

The ornamental design for an electric cord keeper, as shown and described.

DESCRIPTION

FIG. 1 is a front and upper right perspective view of an electrical cord keeper in a condition of use showing our new design. The broken line showing of the electric cords and wall receptacle is included for the purpose of illustrating environmental structure only and forms no part of the claimed design;

FIG. 2 is front and upper right exploded perspective view of the electrical cord keeper;

FIG. 3 is a front and upper right perspective view of the assembled electrical cord keeper shown in the non-use condition.

FIG. 4 is a top plan view thereof;

FIG. 5 is a front elevational view thereof;

FIG. 6 is a left side elevational view thereof;

FIG. 7 is a rear elevational view thereof; and,

FIG. 8 is a front elevational view thereof with all members removed except for the base.
